UNITED STATES PATENT OFFICE.

RALPH S. CLARKE, OF WALPOLE, MASSACHUSETTS, ASSIGNOR TO WANDEL SCREEN MANUFACTURING COMPANY, A CORPORATION OF MASSACHUSETTS.

DRIVING-GEAR FOR ROTARY PULP-SCREENS.

1,138,192.

Specification of Letters Patent.

Patented May 4, 1915.

Application filed July 6, 1914. Serial No. 849,159.

To all whom it may concern:

Be it known that I, RALPH S. CLARKE, a citizen of the United States, residing at Walpole, in the county of Norfolk and State 5 of Massachusetts, have invented certain new and useful Improvements in Driving-Gear for Rotary Pulp-Screens, of which the following is a specification, reference being had to the accompanying drawings, forming 10 part thereof.

This invention relates to improvements in mechanism for effecting the intermittent rotation of the pulp gathering cylinders or screens of pulp screening machines to progressively carry the pulp gathered thereby 15 to positions to be acted upon by the water sprays.

One object of this invention is to simplify the construction of driving gear for rotary 20 pulp screens having vibratory movement in order to reduce the number of gears and their shafts and bearings with their attaching devices.

Another object of the invention is to so 25 construct a pulp screen having duplex rotary pulp gathering screens and means for effecting vibratory action of said screens that the reaction of the screens is resisted in a manner to effect the intermittent rotation 30 thereof.

Other objects of the invention will appear from the following description.

The invention consists in such novel features of construction and combination of 35 parts as shall hereinafter be more fully described and pointed out in the claims.

Figure 1, represents an end elevation of 40 a pulp gathering machine or screen of the nature herein referred to and illustrating the new invention, portions of the same being broken away. Fig. 2, represents a plan view of portions of the same.

Similar characters of reference designate 45 corresponding parts throughout.

Pulp gathering machines of the nature 50 herein referred to usually comprise a vibratory pulp gathering member, ordinarily a cylindrical screen, and mechanism for moving said member during its vibration whereby the pulp gathered by such member is moved to a point at which it is subjected to a shower of water which tends to carry the finer particles of pulp through interstices of 55 the screen or pulp gathering member, such screening operation being assisted by the

vibratory movement of the pulp gathering member. In machines of this character in which rotary screens have been employed it has been customary to rotatably mount the screens in knocker arms, so called, pivotally mounted on the frame of the machine and having their ends free, for a limited movement, and provision has been made by means of rotatable knocker ratchets or cams having steps to vibrate said free ends of said 60 knocker arms. The rotation of said screens has been effected through trains of gears mounted on shafts which latter are journaled in bearings many of which are secured to the machine frame or parts of the 65 machine by bolts. Under the continued strokes of the knocker cams against the striker blocks of the knocker arms the vibration of the parts is transmitted throughout the entire machine, the securing means 70 for the various bearings and other parts of the machine become loosened while the 75 shafts, their bearings, and the pitch points of the several gears become unduly worn.

As shown in the drawings but one end 80 portion of the machine is illustrated, it being understood that the other end of the machine is of approximately similar construction. Parts of the machine heretofore well known and which do not necessarily form 85 part of this invention are also omitted.

In carrying this invention into practice, I provide a pair of end frames as 5 between which is located the usual pulp pan or basin 6, indicated. The end frames as 5 have the 90 studs 7, 7 on which are pivoted the arms 8, 8 having the laterally extending bearings 9, 9, to receive journaled members of the pulp screens, and the depending member 10, 10 provided with the slidably adjustable blocks 95 11, 11 having the contracted followers 12, 12 having curved ends. In suitable bearings is journaled the shaft 13 which may be rotatably driven in any usual or well known manner and is provided with the cams as 14 100 having the projections on spurs 15, 15 and the recesses or stops 16, 16 the outline of which is a succession of regular curves, outward and inward whereby the end of the followers 12, 12 may follow said outline and 105 may be at all times sustained thereby against the stress of the arms 8, 8.

The cylindrical screens 17, 17 are of any usual construction and having the cylindrical end members 18, 18 which are rotatably 110

sustained by the bearings 9, 9 of the arms 8, 8. On each of these cylindrical members 18, 18 is clamped the split collar 19 having the peripherally grooved member 20 and the 5 perforated lugs 21, 21 which are drawn by the bolts 22, 22 to clamp the collar 19 to cylindrical member 18. Mounted on the frames as 5 are the brackets 23, 23 having pivot pins 24, 24 carrying the eccentrics 25, 10 25, which are rotatably adjustable on said pins and, on the peripheries of said eccentrics 25, 25 are mounted the bearing rings 26, 26 of the arms 27, 27 which arms have at their outer ends the wedges 28, 28 shaped 15 to frictionally engage the side walls of the peripheral groove in member 20 of collar 19. Springs 29, 29 are attached to said arms 27, 27 and to the studs 30, 30 fixed on the frames as 5 and said springs act constantly to draw 20 the arms 27, 27 in directions to engage their wedges 28, 28 with the grooves of members 20, 20 the points of coöperation between said wedges and said grooves being determined by the adjustment of the eccentrics 25, 25 25 whereby the extension of said arms 27, 27 from the axes of the pins 24, 24 may be varied.

By reference to Fig. 1 of the drawing it will be seen that when shaft 13 and its cams 30 as 14 are rotated the followers 12, 12 of the blocks 11, 11 will ride outward on the projections 15, 15 of said cams as 14 whereby the free ends of arms 8, 8 will be caused to swing outward, thus swinging upward the 35 bearings 9, 9 of said arms 8, 8, and moving the grooved members 20, 20 in releasing directions relative to the wedges 28, 28 until the highest points of said cam projections 15, 15 pass said followers 12, 12 after which 40 said followers will follow inward on the peripheries of said cams until they reach the lowest points of the recesses 16, 16. At the time the arms 8, 8 and their bearings 9, 9 begin their reactive movement the tendency 45 of the cylindrical screens 17, 17 is to follow the movement of said bearings 9, 9 but such movement of the screens 17, 17 is prevented by the engagement of the wedges 28, 28 with

the grooved members 20, 20 of collars 19, 19 and such engagement of the wedges 28, 28 is 50 sufficient to sustain said collars 19, 19 and their screens at peripheral points while the overbalanced weight of the screen laterally from said sustained points causes the collars 19, 19 and their attached parts to move 55 relatively until the cylindrical members 18, 18 of the screens again seat themselves in the bearings 9, 9. This operation is of course repeated as each cam projection 15 passes by one of the followers 12 so that at 60 each vibratory movement of the screens 17, 17 they are rotatively advanced.

While I have herein shown the cams as 14 furnished with their projections 15 and with a corresponding number of depressions 16, 65 16 it is obvious that the number of such parts may depend somewhat upon the size of the cam 14 or upon the speed at which it is desired to rotate said cam, one purpose of this cam being to utilize the recesses or 70 parts 16, 16 of the cams as 14 as stops to limit the inward movement of the followers 12, 12 toward the axis of the cams as 14 without undue jar to the machinery whereby the use of the cushioned buffers ordinarily employed is avoided. 75

Having thus described my invention I claim as new and desire to secure by Letters Patent—

The combination with a pulp screen having a bearing, means for effecting vibratory motion of said bearing, a pulp screen having a cylindrical extension journaled in said bearing, a split collar clamped on said member and having a peripheral groove, a pin fixed on the machine frame, an eccentric sleeve rotatable for adjustment on said pin, an arm having a bearing sleeve embracing said eccentric and, at its free end a wedge adapted to engage the groove of said collar, 90 and a spring acting to draw said wedge arm toward said collar.

RALPH S. CLARKE.
